UNITED STATES PATENT OFFICE.

LESLIE HOPPER PITZER, OF GARDEN CITY, KANSAS.

BUSHING REMOVER.

Application filed September 22, 1921. Serial No. 502,433.

To all whom it may concern:

Be it known that I, LESLIE H. PITZER, a citizen of the United States, residing at Garden City, in the county of Finney, State 5 of Kansas, have invented a new and useful Bushing Remover; and I do hereby declare the following to be a full, clear, and exact description of the invention, such as will enable others skilled in the art to which it 10 appertains to make and use the same.

The invention relates to bushing removers and has for its object to provide a device of this character particularly adapted for punching bushings from pistons of internal 15 combustion engines in such a manner that strain will not be placed on the piston.

A further object is to provide a bushing remover for pistons, said bushing remover comprising a vertically movable punching 20 member, detachable punching elements adapted to be attached to the lower end of the punching element and removable bushings carried by a horizontally disposed arm and in axial alignment with the punching 25 element and forming the female member of the punch into which the bushing is forced as it is removed and also forming means for engaging the inner side of the piston adjacent the bushing for preventing the bending 30 strain on the piston as a whole during a bushing removing operation.

With the above and other objects in view the invention resides in the combination and arrangement of parts as hereinafter set 35 forth, shown in the drawings, described and claimed, it being understood that changes in the precise embodiment of the invention may be made within the scope of what is claimed without departing from the 40 spirit of the invention.

In the drawings:

Figure 1 is a side elevation of the bushing removing press, showing a portion of the piston supporting arm which supports 45 the piston, said arm being broken away to show the bushing receiving recess therein.

Figure 2 is an enlarged detail vertical sectional view through a portion of the piston supporting arm and the punching carrying 50 member, showing a bushing being removed from a piston.

Figure 3 is a top plan view of the flanged bushing disposed in the recess of the piston supporting arm.

55 Referring to the drawing, the numeral 1 designates a vertically disposed frame,

which frame is provided with a base 2, which may rest on the ground or any suitable support and spaced horizontally disposed arms 3 and 4. Vertically movable in 60 a bearing 5 of the arm 3 is a rack bar 6, with which rack bar a pinion 7 meshes, and when rotated through the medium of the handle 8 moves the rack bar 6 up or down according to the direction of rotation of the pinion 65 7. The lower end of the rack bar 6 is provided with a chamber 9, which chamber receives a reduced portion 10 of a punch member 11, said punch member being held in the chamber 9 by means of a set screw 12 which 70 is threaded into the lower end of the rack bar 6 and into engagement with the reduced portion 10. The punching member 11 is provided with an annular flange 13, which flange engages the outer periphery 14 of a 75 piston 15 during a punching operation and limits the downward movement of the punching element 11. The lower end of the punching member 11 is provided with a reduced portion 16, thereby forming a portion 80 adapted to engage within the chamber 17 of the piston bushing 18, and also forming a shoulder 19 which engages the upper end of the piston bushing 18 for forcing said bushing from the wrist pin bushing aperture 20, which aperture extends through the wall of the piston 15 and through the boss 21 which extends inwardly from the inner 85 side of the piston. Disposed within a recess 22 in the arm 4 of the frame 1 is a flanged 90 bushing 23, the flange 24 of which rests upon the upper side 25 of the arm 4 and forms means for engaging the boss 21 of the piston in such a manner that no strain will be placed on the piston as a whole and only 95 pressure or strain applied to the piston adjacent the bushing receiving aperture 20, by the engagement of the flange 24 with the boss 21. It is to be understood that different sized punching elements 11 may be utilized 100 according to the type and size of piston and bushing and that different sized flanged bushings 23 may be utilized according to the size and type of punching element 11 used.

From the above it will be seen that a 105 bushing-punch is provided for removing bushings from pistons in such a manner that no strain will be placed on the piston as a whole which is a common difficulty at the present time and therefore bending or 110 forcing the piston out of shape is obviated. The device may be utilized for placing or

replacing bushings as well as removing bushings, and it is to be understood that although the device has been described as a bushing remover, that it is equally applicable to both purposes.

The invention having been set forth what is claimed as new and useful is:—

1. A bushing punch for punching bushings from internal combustion engine pistons; said punch comprising a frame, horizontally disposed arms carried by said frame and spaced from each other, one of said arms forming a piston support and adapted to be received within a chamber of the piston, a flanged bushing disposed in said piston supporting arm and adapted to engage the inner side of a piston adjacent a piston bushing, a vertically movable rack and pinion operated punching bar disposed above the piston supporting arm and in axial alignment with the flanged bushing, said punching bar having its lower end provided with a punching element adapted to enter within the outer end of a piston bushing and a shoulder carried by said punching element and adapted to engage the outer end of the piston bushing in such a manner that as the punching bar is forced downwardly, the piston bushing will be forced into the flanged bushing carried by the supporting arm.

2. A piston bushing removing punch, said

punch comprising a supporting arm adapted to enter the chamber of a piston, a flanged bushing carried by said arm adapted to engage the boss of a piston adjacent the bushing to be removed and a punching element provided with a shoulder adapted to engage the outer end of the piston bushing and force said bushing into the flanged bushing carried by the supporting arm.

3. A piston bushing removing punch, said punch comprising a supported arm adapted to enter the chamber of a piston, a detachable flanged bushing carried in a recess of said supporting arm and having its flange engaging the outer face of the arm, said flange being adapted to engage the boss of a piston adjacent the bushing therein, a punching bar axially aligned with said flanged bushing and a detachable punching element carried by said punching bar and adapted to engage the outer end of the piston bushing for forcing said bushing from its place in the piston and into the flanged bushing.

In testimony whereof I have signed my name to this specification in the presence of two subscribing witnesses.

LESLIE HOPPER PITZER.
